(57) **CLAIM**

We claim the ornamental design for a window operator handle and cover, as shown and described.

DESCRIPTION

FIG. 1 is a left front isometric view of the window operator handle and cover according to the invention;
FIG. 2 is a right front isometric view of the window operator handle and cover depicted in FIG. 1;
FIG. 3 is a front elevation view of the window operator handle and cover depicted in FIG. 1;
FIG. 4 is a left elevation view of the window operator handle and cover depicted in FIG. 1;
FIG. 5 is a right elevation view of the window operator handle and cover depicted in FIG. 1;
FIG. 6 is a top plan view of the window operator handle and cover depicted in FIG. 1;
FIG. 7 is a rear elevation view of the window operator handle and cover depicted in FIG. 1; and,
FIG. 8 is a bottom plan view of the window operator handle and cover depicted in FIG. 1.
The broken lines shown in the drawings represent portions of the window operator handle and cover that form no part of the claimed design.

1 Claim, 3 Drawing Sheets
